TYPEWRITING MACHINE

Frederick A. Hart, Stamford, Conn., assignor
to Remington Typewriter Company, Ilion,
N. Y., a corporation of New York

Application October 8, 1932, Serial No. 636,867

38 Claims. (Cl. 197—128)

My invention relates to typewriting, and combined typewriting and computing and like machines, and more particularly to so-called book-keeping or billing machines.

5 The main object of the invention, generally stated, is to provide an improved machine of the character specified which may be rapidly conditioned for the speedy and accurate handling and collating of work sheets and for simultaneously entering items thereon.

A further object of the invention is to provide a machine of the character specified in which lower case as well as upper case characters may be employed.

15 Another object of the invention is to provide improved means for automatically locking the numeral printing keys and the parts controlled thereby against operation when the machine is conditioned for introducing and collating the work sheets.

20 A still further object of the invention is to provide means for so disposing the feed rolls when they are withdrawn from the platen that they will act as a guide for directing work sheets introduced into the machine from in front of, to and beneath the platen.

A further object of the invention is to provide means of the character hereinbefore referred to which may be embodied in existing machines

25 without modifying, or materially modifying, the existing structural features thereof.

Still another object of the invention is to provide means by which the line indicator will be moved from indicating position at the first part 35 of the movement of the feed rollers towards the platen and will be moved to ineffective or non-indicating position at the first part of the movement of the feed rollers away from the platen.

To the above and other ends which will hereinafter appear, my invention consists in the features of construction, arrangements of parts, and combinations of devices set forth in the following description and particularly pointed out in the appended claims.

45 In the accompanying drawings, wherein like reference characters indicate corresponding parts in the different views—

Fig. 1 is an enlarged, detail, fragmentary, vertical, fore and aft sectional view of the carriage 50 of a typewriting machine equipped with devices of my invention; the parts being shown in this view conditioned to proceed with the writing. This view corresponds to the section taken on the line 1—1 of Fig. 3 and looking in the direction of the arrows at said line.

Fig. 2 is a like view of the same showing the parts conditioned to receive the work sheets, the section being taken on the line 2—2 of Fig. 3 and looking in the direction of the arrows at said line.

Fig. 3 is an enlarged, detail, fragmentary, top plan view, with parts in section, of the left-hand portion of the carriage.

Fig. 4 is a detail, fragmentary, top plan view, with parts in section, of the right-hand portion 65 of the carriage.

Fig. 5 is an enlarged, detail, fragmentary, perspective view showing one of the feed rollers and the means for supporting and controlling the same, together with some of the associated 70 parts.

Fig. 6 is an enlarged, detail, fragmentary, vertical, fore and aft sectional view of the deflector plate carried by the top plate of the machine and some of the associated parts, the section being taken on the line 6—6 of Fig. 4 and looking in the direction of the arrows at said line.

Fig. 7 is a detail, transverse, vertical, sectional view of the same taken on the line 7—7 of Fig. 6 and looking in the direction of the arrows at 80 said line.

Fig. 8 is a detail, vertical, central, sectional view of the machine with some of the parts omitted.

Fig. 9 is an enlarged, detail, fragmentary, top 85 plan view, with parts in section, of a portion of the means for controlling the key locking devices; the view corresponding to a section taken on the line 9—9 of Fig. 8 and looking in the direction of the arrows at said line.

Fig. 10 is a horizontal, sectional view of the same taken on the line 10—10 of Fig. 8 and looking in the direction of the arrows at said line.

Fig. 11 is a vertical, sectional view of the same taken on the line 11—11 of Fig. 8 and looking 95 in the direction of the arrows at said line.

Fig. 12 is an enlarged, detail, sectional view of one of the feed rollers and the means for mounting the same, together with some of the associated parts; the section being taken on the line 12—12 of Fig. 3 and looking in the direction of the arrows at said line.

Fig. 13 is a detail, perspective view showing the parts which constitute a carrier for one of the feed rollers.

Fig. 14 is a sectional view corresponding to Fig. 1 with some of the parts omitted and showing the parts disposed as they appear when the feed roller is advanced to a position close to but 100 105 110 out of contact with the platen or the work sheets thereon.

Fig. 15 is an enlarged, detail, sectional view taken on the line 15—15 of Fig. 3 and looking in 5 the direction of the arrows at said line.

Fig. 16 is a diagrammatic side elevation disclosing the devices of my invention as they appear when the key lock is released and the platen is in the lower case position and the feed rollers 10 are applied to the platen.

Fig. 17 is a like view of the same except that the parts are shown as they appear when the feed rollers are moved away from the platen and the key lock is moved to locking position while 15 the platen still remains in the lower case position.

Fig. 18 corresponds to Fig. 16 except that the parts are shown as they are disposed when the platen is shifted to upper case position.

Fig. 19 corresponds to Fig. 17 except that the 20 parts are shown as they are disposed when the platen is in upper case position.

I have shown my invention in the present instance embodied in a "Remington electrified bookkeeping machine" such as is disclosed in my 25 application Ser. No. 510,941, filed Jan. 24, 1931, but have only shown so much of said machine as is necessary to arrive at an understanding of the present invention in its embodiment therein.

While the features of the present invention 30 were designed primarily for embodiment in the above-mentioned machine and may be included therein without modifying, or materially modifying, the existing structural features thereof, it should be understood that the invention is not 35 restricted to the use in such machine but may be employed in typewriting and like machines generally wherever found available.

The Remington electrified bookkeeping machine has a non-shifting platen and writes only 40 upper case characters. The means employed in said machine for facilitating the introduction of work sheets into the machine from in front of and beneath the platen and for handling the collating work sheets are like those disclosed in 45 the application of Frederick A. Hart and Sigurd L. Walsoe, Ser. No. 221,543, filed Sept. 23, 1927.

The present invention is in the nature of improvements on the construction disclosed in said last mentioned application and provides for writing lower case characters as well as upper case characters, the work sheet controlling means and the parts associated therewith functioning in either case position to which the platen may be shifted.

Before describing the construction, brief reference will be made to one of the various uses to which the invention may be put.

The machine being first conditioned for receiving work sheets, a record sheet R with an outer 60 or underlying carbon sheet C are introduced into the machine from the rear of the platen between the platen and the upper curved deflector plate beneath the platen. The leading ends of these sheets are brought forward and upward 65 and arranged beneath the upper feed rollers at the top of the platen. A statement sheet S, ledger sheet L and interposed carbon sheet C are then introduced rearward into the machine from in front of and beneath the platen, with the statement sheet outermost. These last mentioned 70 sheets are inserted bottom ends first into a separate channel between the upper and lower curved paper deflectors beneath the platen. When these sheets S and L have been properly collated with 75 reference to each other and the previously intro-

duced and positioned record sheet R and the printing line, the feed rollers are applied and the machine operated to effect a simultaneous entry of the items on the statement sheet S, ledger sheet L and record sheet R. When the entries are finished, the statement sheet and the ledger sheet are removed and new ones inserted; the record sheet and its companion carbon sheet C remaining in the machine and taking an accumulation of the items written on the various statement and ledger sheets.

The foregoing is but one of the various uses to which the present machine may be put and it is one of the general objects of the present invention to provide means for rapidly, successively and accurately introducing and collating work sheets in the machine, as hereinbefore indicated.

The Remington electrified bookkeeping machine, and that disclosed herein, has a main frame comprising two sections 1 and 2 hinged together at 3 in the rear thereof to enable the upper section 1 to be swung back on the lower section to give access to the parts contained within the frame and to move down to the position of use shown in Fig. 8. Power actuated mechanism 100 (not shown) is contained within the base section 2 of the frame and coacts with various parts controlled thereby, such for example as the numeral printing type bars 4 and alphabet printing type bars 5 as well as other parts of the machine. 105 The construction is such that the coacting parts contained within the base section 2 and the upper section 3 do not interfere with the relative movement of the frame sections to and from one another. The upper section of the frame is provided with corner posts 6 (see Fig. 8) on which a top plate 7 is supported.

The carriage of the machine comprises a truck 8 supported at front and rear on crossed bearing rollers 9 to travel from side to side of the machine over the top plate. A platen frame 10 which supports a cylindrical platen 11 is mounted for vertical case shifting movement on parallel links 12. The case shifting movement of the platen frame to and from upper case position is 110 limited by adjustable stops 13 and 14 which coact with coiled spring 15 (see Fig. 3) surrounding the bearing of the platen shaft.

For the purpose of the present invention it is sufficient to illustrate a manually actuated case 125 shift mechanism, although it will be understood that power actuated case shift mechanism may be employed. In the present instance the case shift mechanism includes a grooved bearing roller 16 (see Fig. 8) carried by a cross bar 17 that 130 constitutes a part of the platen frame. This roller is supported on a shift rail 18 carried by upright supporting links 19 pivoted at their lower ends, at 20, to lever arms 21 arranged at opposite sides of the machine and connected to move 135 together by suitable means (not shown). Each lever arm 21 is pivoted to the upper section 1 of the frame, at 22, and extends forward of its pivot and is provided with a case shift key 23. A counter-balance spring 24 is connected at one end to 140 each of the links 19 and is anchored at its opposite end to the top plate 7 of the machine. A depression of either of the case shift keys 23 is effective to move the platen from its normal lower case position to its upper case position.

The numeral and alphabet printing type bars 4 and 5 are adapted to impact against the front face of the platen, or the paper carried thereby, as indicated in Fig. 12 in which the dot and dash line a represents the printing line. These type 145 150

bars may be actuated in any suitable manner such, for example, as indicated in my hereinbefore mentioned application in which numeral printing key levers 25 are fulcrumed on a fulcrum bar 26 secured to the frame section 1 and each provided with a finger key 27. Each numeral key is provided with a depending trip 28 by which power controlled actuating means (not shown) for the numeral printing type bars 5 and 10 the computing mechanism of the machine are actuated. Each numeral printing type bar 4 is operatively connected to a sub-lever 29 pivoted at 30 and connected at 31 to a sub-lever 32 that is fulcrumed on the fulcrum bar 26 and coacts 15 with a power actuated member 33 to effect an operation of the corresponding type bar on the depression of a numeral printing key 27.

The mechanism of my present invention for controlling and collating the work sheets will 20 now be described.

The platen frame 10 which supports the platen 11 comprises a front cross bar 34 (see Fig. 1). The front face of this cross bar coacts with a centrally disposed bearing roller 35 pivoted at 25 36 on the front cross bar 37 of the carriage truck. This roller receives any forward thrust of the platen frame and accurately guides the platen frame in its case shifting movement.

Arranged beneath the platen is an upper curved 30 deflector plate 38 which extends throughout the length of the platen and is supported at the rear edge thereof on a rod 39; the deflector plate terminating at its forward edge below the printing line. This deflector provides a channel 40 between the platen and said deflector plate to receive a forwardly introduced record sheet R and a companion carbon sheet C which are carried forward and upward beneath the usual set of feed rollers 41 carried by spring pressed arms 42 in 35 the usual manner. The cross bar or supporting spindle 43 for the feed rollers 41, together with the arms 42, are in the nature of a pivoted spring pressed bail that may be swung upward to ineffective position or down to the effective position, 40 shown in Fig. 1.

Beneath the curved deflector plate 38 is a second curved deflector plate 44 maintained spaced apart from the deflector plate 38 by end spacing bars 45 providing a rigid connection between 45 the two deflectors which constitute a chute. A second channel 46 is thus provided between the two deflectors for the backward insertion from in front of and beneath the platen of a statement sheet S and ledger sheet L and an interposed carbon sheet c. Pivoted at 47 along the front end of the fixed deflector plate 46 is a deflector section 48 which forms a continuation of the deflector 46 and terminates at its front end below the printing line. This pivoted section 48 has a pivotal movement from the position indicated in Fig. 1 to that indicated in Fig. 2. This is to provide an enlarged open mouth at the receiving end of the channel 46 to receive and direct the work sheets S and L with the interposed carbon sheet c into 50 said channel. When the machine is in condition for writing, as shown in Fig. 1, the pivoted section 48 is closed against the work sheets in the channel 46 and holds them more or less snug against the face of the platen. The opening and closing of this pivoted deflector section 48 is automatically controlled, as will hereinafter more clearly appear.

The feed rollers which coact with the platen and by which the work sheets are controlled and 55 fed with the aid of the platen are preferably ar-

ranged in two sets. Outside terminal or marginal feed rollers 49 are employed ordinarily to coact with the marginal portions of a comparatively wide ledger sheet L and its overlying carbon sheet c, whereas the intermediate feed rollers 50 are intended to coact with the marginal portions of a narrower statement sheet S. Both sets of these feed rollers cooperate with the platen above the printing line and are arranged in substantial alignment as indicated in Fig. 4. These feed rollers are mounted and controlled for movement from the effective position shown in Fig. 1, down to the ineffective position shown in Fig. 2 where they not only offer no obstruction to the introduction of a work sheet into the channel 46, but are positioned where they constitute a support and guide for the work sheets as they are introduced into said channel. The means for thus supporting and guiding the feed rollers and for applying them with an effective pressure to the work sheet will now be described.

Referring more particularly to Fig. 12 it will be seen that each feed roller, whether it be a feed roller 49 or 50, is supported on a pivot rod 51 which unites two slides or feed roller carriers 52 arranged on opposite sides of the feed roller. These slides are fixedly united not only by the pivot rod 51 but by a cross rod 53. Each slide at its forward end is provided with a longitudinally extending slot 54 in which is received a rock shaft 55 to provide a support for and afford a sliding and pivotal movement of each of the slides 52 thereon. Each slide is also provided with an aligned cam slot 56 which extends longitudinally of its slide and has at its forward end an upwardly directed extension slot 57. A guide pin 58 is received in each cam slot 56-57 and coacts therewith to guide and determine the direction of movement of the slides from the full line to the dotted line position in Fig. 12 and vice versa; the slots 56-57 operating in 105 the nature of cam slots which coact with the relatively fixed pins 58. When, therefore, pressure is exerted on the slides by their toggles to apply the feed roller as will hereinafter appear, the slides will first be moved upward from the ineffective 110 position, shown in Fig. 12 to the effective position, indicated in full lines in this figure. In withdrawing a feed roller this movement of the slides will be reversed.

The supports for each feed roller comprise two 115 sheet metal bracket plates 59 shown in detail in Fig. 13. Each of these plates carries one of the guide pins 58 by which the companion slide 52 is supported intermediate its ends, and is apertured at 60 to provide a pivotal bearing for the 120 bracket plate or support on the rock shaft 55. An inwardly extending lug 61 on each support 59 constitutes a bearing face against which a plate 62 is seated when the parts are assembled, as shown in Fig. 1. A central aperture 63 in 125 the plate 62 receives a headed screw 64. The forward threaded end of this screw is received in a tapped opening in a cross bar 65 connected to a U-shaped supporting bracket 66. Each bracket 66 has a tongue-and-groove engagement, as indicated at 67, with a bar 68 secured by screws 69 to the front cross bar 34 of the platen frame and extending throughout, or substantially throughout, the length thereof. The purpose of this 130 mounting of each bracket 66 on the supporting bar 68 is to afford an adjustment of each of said brackets together with the parts carried thereby to any desired position longitudinally of the platen so that each feed roller, its supporting 135 140 145 150

guiding and controlling means, may be adjusted as a single unit longitudinally of the platen.

A coiled expansion spring 70 is provided between the head of each screw 64 and the companion plate 62. The force of this spring tends therefore, to maintain the associated carriers or brackets 59 against pivotal displacement from the position they normally assume in the machine. In such position a stop pin 71 on each plate 59 bears against the companion upright arm of the associated U-shaped bracket 66 and limits the pivotal movement of the carrier or plate in one direction under the pressure of its spring 70. When, however, the associated slides 52 are moved to the full line position shown in Fig. 12, the companion feed roller will be caused to bear with a positive pressure against the platen and by riding up on the curved face thereof will flex the spring 70, and the reaction of said spring will be exerted against the feed roller to maintain it under spring pressure against the platen or the work sheet thereon.

There is a distinct advantage in making the support for each of the feed rollers in two separate members 59 as shown, in that the parts are cheaper to manufacture, and they can be more readily assembled with the companion parts of each unit. Moreover, by making the supports in two parts as indicated, they may be used in employing rollers of different lengths by merely increasing or decreasing the length of the associated member 62 and the spacing sleeves to be hereinafter described.

The means for moving the feed rollers 49 and 50 to and from effective position as hereinbefore described will now be set forth.

Each feed roller is moved to and from effective position by toggles, the straightening of the toggles positively applying the feed rollers, as indicated in Figs. 1 and 5, and the breaking of the toggles moving the associated feed roller to ineffective position, as shown in Fig. 2. Each toggle comprises a toggle link 72 pivotally connected at one end to the cross rod 53 which unites the companion slides 52, and pivoted at its other end, at 73, to a toggle lever 74. Each toggle lever 74 is mounted on the rock shaft 55 and extends upward and forward therefrom where it is connected to a finger piece 75 that is interposed between the two companion toggle levers 74. Companion toggle links 72 are maintained spaced apart on the cross rod 53 by spacing sleeves 76 and the associated toggle levers 74 are maintained spaced apart and in proper position between the upright arms of the bracket support 66 by spacing sleeves 77 and the companion finger piece 75. As a finger piece 75 is shifted forward, the companion toggle members 74, 72 will be straightened to the Fig. 1 position, thereby first elevating the companion slides 52 from the Fig. 2 position. In this movement the slides receive a pivotal motion around the rock shaft 55 until the lowermost horizontal part of the cam slot 56 is reached when the slides receive a further rectilinear movement to bring the feed rollers in contact with the platen and the work sheet thereon, as indicated in Fig. 1. The straightening of the toggle exerts a positive force against the feed roller to cause it to ride up on the curved surface of the platen and thereby stress the companion spring 70 so that the reaction of said spring will be exerted against the feed roller.

When the finger piece is moved in the opposite direction, the toggle will be broken, thus reversing the movement of the slides 57 and causing them

first to receive a forward rectilinear movement and then a downward movement from the position shown in the dotted line position in Fig. 12 and to that indicated in Fig. 2; this latter or downward movement being due of course to the fact that the pins 58 at this time engage the upright portions 57 of the cam slots and cause the slides to receive a pivotal downward movement at this time.

Depending somewhat on the character of the work to be performed, the toggle levers 74 may be connected to the rock shaft 55 to be turned thereby, or the toggle lever 74 may be loosely mounted on the shaft to receive a movement independently thereof under control of the finger pieces 75. The toggle levers 74 of the outermost feed rollers 49 are usually connected to the rock shaft to turn therewith, each of such toggle levers being provided with an integral spline projection 78 (see Fig. 14) that takes within a V-shaped spline groove 79 in the rock shaft 55. In a like manner the toggle lever 74 for the inner set of feed rollers 50 may be connected to turn with the rock shaft 55, but preferably these are devoid of the spline projections 78 and are free to turn independently on the rock shaft 55, so as to enable the feed rollers 50 to be separately applied to the work sheets with the aid of the finger pieces 75.

The rock shaft 55 preferably extends throughout the length of the carriage and is supported near its ends in bearing openings in the side plates of the platen frame 10 as well as receiving support intermediate its ends in the brackets 66. The left-hand end of this shaft is extended beyond the companion side plate of a platen frame and has a tooth segment or sector 80 secured thereto, as shown in Figs. 3 and 5. This tooth segment 80 engages a companion sector 81 and is provided with a hub 80^a which is preferably adjustably secured to the rock shaft 55 by two screws 80^b, 80^c. These screws are received in tapped openings in the hub 80^a and their pointed ends extend into a V-shaped groove 79 in the shaft 55, one screw bearing against one side of the groove and the other against the other side of the groove, as shown in Fig. 15. By backing up one screw and advancing the other a rotative adjustment of the sector 80 on the shaft 55 in either direction may be readily effected. The sector 81 is mounted on a short shaft 82 that receives a bearing in the companion side plate of the platen frame 10. The inner end of this shaft 82 is fixedly connected to a crank arm or manually controlled actuating member 83 that extends upward and is provided with a finger piece at the upper end thereof. A rearward movement of the arm 83 from the Fig. 2 position to the Fig. 1 position, is effective to transmit an anti-clockwise movement to the rock shaft 55 which in turn is effective to straighten all of the toggles that are connected to the rock shaft and to move the feed rollers thus connected from the Fig. 2 to the Fig. 1 position and apply such feed rollers to the platen or the work sheets thereon. A movement of the arm 83 in the opposite direction is effective to withdraw the feed rollers connected therewith from the platen or from the Fig. 1 to the Fig. 2 position. The outside terminal feed rollers 49 having been applied by movement of the rock shaft 55 in the manner described, are effective to engage and hold the previously adjusted wider ledger sheet L in position. The subsequently introduced, relatively narrower, statement sheet S and carbon sheet c may then be placed in position and

collated with reference to the ledger sheet and the separately applied feed rollers 50 may then be moved to effective position to engage the statement sheet.

5 In order to facilitate the proper adjustment of the work sheets with reference to the printing line, I have provided a line indicating device or wire 84 carried by arms 85 secured to a rock shaft 86 near the ends thereof. A contractile spring 87 is secured at one end to one of these arms 85 and is anchored at its other end to a pin 87^a that projects in from one of the side plates of the platen frame 10. The force of this spring is exerted to move the line indicator 84 to effective, indicating, position, as shown in Fig. 1. One of the arms 85 is extended upward to form an arm or actuating member 85^a provided with a finger piece 88 at the terminal portion thereof. The upwardly extending arm 85^a coacts with a stop 89 as shown in Fig. 1 to limit the movement of the arms 85 and the line indicator 84 carried thereby in one direction or towards the platen. The stop 89 is eccentrically mounted, as indicated at 90 in Fig. 1 so as to provide for adjusting the stop.

25 While the arm 85^a may be actuated at will to control the line indicator means also are provided for automatically actuating the line indicator under control of the arm 83. It is desirable to move the line indicator 84 to its indicating position at the first part of the movement of the feed rollers toward the platen, and to move the line indicator away from effective, or indicating, position at the first part of the movement of the feed rollers away from the platen. The means for accomplishing these results will now be described.

45 Referring more particularly to Fig. 5, it will be seen that a headed screw 91 projects laterally from the arm 83 and constitutes a pivotal connection for a link 92. The opposite end of this link carries a pin 93 which projects through the horizontal slot 94 in a fixed guide plate 95 secured by screws 96 to the adjacent side plate of the platen frame 10. The outer end of this pin 93 is headed, as indicated at 97 in Fig. 3, to retain the pin 93 in its guide slot 94. A second link 98 is pivotally connected to the pivot screw 91 and is loosely seated thereon to afford a lateral movement of the link 98 towards and from the link 92. The lower end of the link 98 is mounted in a like manner on the pin 93. A leaf spring 99 is secured intermediate its ends at 100 to the link 92 and bears at its free ends against the link 98 to normally maintain said link 98 against the head of the screw 91 and the inner head of the pin 93. The link 98 intermediate its ends is provided with a laterally extending projection or abutment 101, opposite sides 102 and 103 of which are inclined to form cam faces for purposes which will hereinafter more clearly appear. In the movement of the arm 83 to the rear from the Fig. 2 position, the projection or abutment 101 will engage the upright arm 85^a, as indicated in Fig. 2, at the first part of the motion of the arm 83, and will move the arm 85^a with the arm 83, thereby moving the line indicator from the ineffective, Fig. 2, position to the effective, Fig. 1, position. The movement of the arm 85^a with the lever arm 83 will continue until the arm 85^a reaches its stop 89 and is arrested thereby, as shown in Fig. 14. From a consideration of this figure it will be seen that at this time the feed rollers have not quite reached the platen 11, but are brought sufficiently close thereto to bear against the

work sheets with sufficient pressure to maintain them against accidental displacement but with sufficient freedom to enable the work sheets to be adjusted relatively to the line indicator 84 which at this time has completed its movement to indicating position. When the arm 85^a coacts with the stop 89 as pointed out above, sufficient resistance to the further movement of the arm 83 will be felt by the operator to indicate to her that further rearward movement of the arm 83 should not be exerted until the work sheets L and S have been properly adjusted, and while the parts are maintained in the Fig. 14 position.

80 However, after the adjustment of the work sheets L and S has been effected, the operator will exert a further rearward pressure on the arm 85^a, thereby forcing the link 98 laterally with a camming action against the force of the spring 99 which bears against said link. The effect of thus camming the link 98 to one side is to enable the abutment or cam 101 to ride over and past the arm 85^a while the latter is held against its stop 89, and thus enable the cam 101 to pass to the opposite side of the lever arm 85^a in a position to engage it immediately on the return movement of the arm 83 and its link 98. This relative position of the parts is shown in Fig. 3. Therefore, as soon as the arm 83 is moved forward to release the feed rollers, the arm 85^a will be carried forward with the link 98, thereby withdrawing the line indicator from effective position during the first part of the movement of the feed rollers away from the platen. In this return movement of the arm 83 to its forward position, the arm 85^a will be brought in contact with a stop pin 104 carried by the fixed guide 95 and arrest it, while the arm 83 continues its forward motion independently of the arm 85^a. The effect of this continued forward motion of the arm 83 is to deflect the spring pressed link 98 outwardly towards the link 92 by the camming action of the abutment 101 against the arm 85^a as the cam rides over the arm to a position in front of it, as indicated in Fig. 2. Due to this displacement of the abutment 101 in front of instead of behind the arm 85^a, the parts will be conditioned to move the line indicator to effective position as soon as the arm 83 is next moved rearward to bring about a movement of the feed rollers to effective position.

85 100 105 110 115 120 125 130 135 140 145 150

From an inspection of Fig. 13 it will be seen that each of the plates or brackets 59 is provided with an inwardly extending projection 105 that constitutes a stop for the associated toggle arm 74 to limit the motion thereof and the movement of the toggles to straightened position, as indicated in Fig. 5. This brings the toggle members slightly over the dead center and locks them in such position.

I have provided means in the present construction for automatically lowering the usual ribbon vibrator 106 from normal position when the deflector section 48 is lowered to the open position shown in Fig. 2 and the machine is thus conditioned to receive the work sheets. The ribbon vibrator is carried by an arm 107, as shown in Fig. 2, which in turn is mounted on a ribbon vibrator support, indicated as a whole by the reference numeral 108. This ribbon vibrator support is mounted to move up and down on parallel links 109, springs 110 being employed to normally maintain the ribbon vibrator support in its elevated position. An arm 111 (see Fig. 2) extends upward and forward from the rib-

bon vibrator support 108 and carries an anti-friction roller 112 at the upper end thereof. This roller is adapted to bear against the lower edge of a sheet metal flange 113 which extends throughout the length of the platen and is fixedly secured to the rock shaft 86 on which the arms 83 are mounted. Upwardly extending fingers 114 are also connected to the rock shaft 86 and are adapted to coact with the pivoted deflector section 48, as shown in Figs. 1 and 4, to turn said deflector section around its pivot 47 from the Fig. 2 to the Fig. 1 position when the feed rollers are applied to the platen. When the arm 83 is moved forward to the Fig. 3 position, the pivoted deflector section 48 is automatically moved down to the Fig. 2 position by the turning movement of the fingers 114 with the rock shaft 86 to which they are secured. This same movement of the rock shaft is effective to lower the ribbon vibrator carrier 108, and to lower the vibrator from its normal position and thereby give greater clearance for the introduction of work sheets into the channel 46.

I also have provided means for automatically locking the numeral keys of the machine against actuation at this time. Referring more particularly to Fig. 8 it will be seen that the ribbon vibrator carrier 108 has connected to one of its parallel links 109 a rearwardly extending arm 115 which is fixedly secured thereto. The rear end of this arm carries a pin 116 that is received in the forked end 117 of an arm 118 pivoted to turn on fixed pivot 119. The arm 118 extends rearward beyond its pivot to provide a second arm 120 to which is attached an adjustable device 121 to which is pivoted, at 122, a depending controlling member 123. This controlling member is provided with two cams 124 and 125 and is guided in its up and down movement by the following means.

Referring more specifically to Figs. 9, 10 and 11, it will be seen that the controlling member 123 is received between and embraced on opposite sides by a roller 126 and a disk-like guide member 127 coextensive with the dimensions of the bearing roller 126. The roller and disk-like guide member are supported and maintained spaced apart on a pivot pin 128 riveted at 129 to a bracket arm 130 secured by screws to a second bracket 131, which in turn is secured by screws 132 to the upper frame section 1 of the machine in the rear thereof. The front cam-carrying face of the controlling member 123 coacts with an anti-friction roller 133 which is carried by and extends laterally from one section 134 of a horizontally disposed two-part actuating member or link, the other section of which is represented at 135. Pins 136, 137 project laterally from the members 135 and 134 respectively and are connected by a contractile spring 138. These two sections 134 and 135 of the link have a pin and slot connection indicated at 139, 140, by which the sections may be moved lengthwise relatively one to the other, as will hereinafter more clearly appear. The link section 134 receives a support on the hereinbefore mentioned roller 126 and is guided in its movement thereon by extending it through a guide slot 141 in a bracket arm 142 which forms part of the bracket 130, hereinbefore referred to. The bearing roller 126 therefore constitutes a support at the rear end for the two-part link comprising the sections 134 and 135, whereas the forward end of this link is pivoted at 143 to a depending lever arm 144 mounted to turn on a fixed pivot 145. The lower end of

this lever arm is pivoted to another forwardly extending link 146 which has its forward end pivoted to an arm 147 of a key locking mechanism, which may be of any suitable construction but which as shown in the present instance is of the character disclosed in my application Ser. No. 549,852, filed July 10, 1931. The arm 147 projects from a rock shaft 148 and said shaft also has fixed thereon a locking blade 149 that is adapted to be projected through a slot in a housing 150 that receives a series of locking balls 151 in a channel therein. The housing is also slotted to receive the key levers 152 of the numeral keys 27, so that said levers may be controlled by the locking balls to afford an actuation of only one lever at a time; there being sufficient room between adjacent balls for the reception of only one key lever at a time. If, therefore, one of the key levers 152 is depressed, all of the other of such levers are prevented from being depressed by the closed locking balls of the series. The locking blade 149 when shifted between two adjacent balls has the same effect as the depression of one of the numeral keys so that when said locking blade is forced between adjacent balls all of the 100 numeral keys will be locked against depression.

It will be understood, therefore, that when the parts are conditioned as shown in Fig. 2 for the introduction and collation of the work sheets, this results in lowering the ribbon vibrator support 108 and transmitting motion therefrom through the arms 115, 118, 120 and the controlling member 123 to effect a longitudinal movement of the latter, with the result that one of the cams 125 or 124 thereon will coact with the two-part link 134, 110 135, causing it to be moved forward and through the lever 144 and link 146 to rock the shaft 148 in an anti-clockwise direction. The effect of this is to insert the locking blade 149 between adjacent balls and lock the numeral keys against depression. The parts will be retained in this condition as long as the devices of the paper controlling mechanism, etc., are retained in the position shown in Fig. 2. It follows, therefore, that at this time the printing keys 27 are locked 120 against depression thereby preventing an operation of the parts controlled thereby including the printing instrumentalities and the computing mechanism and results in preventing injury to the machine as well as a false operation. Thus, 125 should the operator at this time be able to actuate the numeral printing type bars, they would be apt to collide with the feed rollers as will be understood from a consideration of Fig. 12; said feed rollers at this time being in a line of travel 130 that intercepts the type bars. Therefore, aside from the possible injury to the parts, a non printing and false operation would follow.

It will be understood that the construction is such that in the case shifting movement of the 135 platen the ribbon vibrator support 108 is automatically elevated by its springs 110 with the platen as the latter is shifted to upper case position. The effect, therefore, of this movement of the ribbon vibrator support is to shift the train 140 of connections intermediate said support and the controlling member 123. From a consideration of Figs. 16, 17, 18 and 19, it will be understood that when the platen is in the lower or normal case position as represented in Fig. 16, and the feed 145 rollers 49 are applied to the platen, an actuation of the arm 83 will result in lowering the ribbon vibrator support 108 to the Fig. 17 position, thereby actuating the controlling member 123 through the intermediate train of connections with the re- 150

sult that the cam 124 will shift the two-part link 134, 135 forward thus bringing about a movement of the locking blade into locking position between the locking balls 151 as shown in Fig. 17, and the 5 parts will remain in this position as long as lever 83 and the parts controlled thereby remain in the Fig. 17 position.

On the other hand, if the platen should be shifted to the upper case position, the result is 10 that the ribbon vibrator support 108 will follow up the shifted platen to the Fig. 18 position in order to enable the vibrator to be maintained in the same relation to the printing line that it does when the platen is in the lower case position.

15 This results in shifting the train of connections between the ribbon vibrator support 108 and the controlling member 123 to the Fig. 18 position. In turn this results in moving the cam 124 upward out of cooperative relation with the anti-friction roller 133 and bringing the cam 125 on 20 the controlling member into cooperative relation with said anti-friction roller, as shown in Fig. 18. It follows therefore that if the arm 83 should be moved forward from the Fig. 18 position to 25 release the feed rollers 49, or all of those which may be connected to the rock shaft 55, then the controlling member 123, through the intermediate train of connections, will be moved to the Fig. 19 position. This results in causing the cam 125 to 30 coact with the anti-friction roller 133 and move the two-part link 134, 135 forward, thus locking the numeral keys against depression. This condition of the parts is illustrated in Fig. 19.

It follows from what has been pointed out 35 above that notwithstanding the fact that the case shifting movement of the platen changes the relation of the train of connections to the key locking mechanism, the latter will, nevertheless, operate effectively in either case position of the 40 platen when the machine is not conditioned to receive the writing, and the lock is automatically released in either case position of the platen when the machine is properly conditioned to receive the writing.

45 The Remington electrified machine is provided with an automatic power actuated carriage return mechanism for returning the carriage to the beginning of the line position when an end of the line is reached and for simultaneously line spacing the work sheets. This condition provides 50 a favorable position of the carriage for withdrawing the written statement and ledger sheets from the machine and for introducing a new statement and ledger sheet into the machine. In 55 the present construction I have provided a directing shield on the top plate 7 that coats with the parts when the carriage is disposed at the right-hand end of its travel, to facilitate the introduction of the new statement and ledger sheets into the machine. This deflector plate and the 60 means for mounting it will now be described.

Referring more particularly to Figs. 4, 6 and 7, it will be seen that a deflector plate, designated as a whole by the reference numeral 153, has a 65 rearwardly and downwardly inclined face 154 that constitutes in effect a continuation of the deflector 48 when the latter is in the open position, as indicated in dotted lines in Fig. 6, thus facilitating a rearward introduction of the new statement and ledger sheets into the channel 46. This deflector terminates at its inner end to the 70 right of the usual type bar center guide 155 and the ribbon vibrator 106 and is preferably inclined at its left-hand end portion, as indicated at 156 in Fig. 4. This deflector 153 may be mounted in

any suitable manner, but I prefer to pivot it at 157 on brackets 158. A stop arm 159 on each bracket supports the deflector in its normal position against the pressure of coiled springs 160, each of which at one end engages the deflector and at its opposite end is anchored on the associated bracket. The pressure of the springs 160 is very light and enables the deflector to be lifted away from its normal position in the event that the closely positioned deflector 48 should collide therewith. I prefer to mount the supporting brackets 158 on the right-hand side of the top plate 7 of the machine for adjustment fore and aft of the machine. This is effected in the present instance by slotting the base of each bracket at 161 and providing headed clamping screws 162, the stems of which enter the slots 161 and engage at their threaded ends in tapped openings in the top plate.

I have hereinbefore pointed out that the members of the two-part link 134, 135 are connected together by a spring 138. The purpose of this connection is to afford a relative movement between the two sections of and a shortening of the link in the event that it should receive a forward thrust under the action of the control member 123 at a time when the ball lock is held in the locked position by a depressed numeral key 27. At this time the locking blade or arm 149 cannot enter between adjacent balls in the ball lock. 100 Due, however, to the provision of the spring 138 no injury can result at this time by an actuation of the arm 83 to condition the machine to receive the work sheets. The effect of this operation would merely result in moving the link section 134 forward against the force of its spring 138 while the forward section of the link is held against forward movement. However, as soon as the operator releases the depressed key 27 and allows it to return to normal position, the 105 force of the spring 138 will move the link section 135 forward, thereby locking the keys against operation until such time as the arm 83 is shifted to condition the machine for writing.

The two-part link 134, 135 has another function which will now be described. An upwardly extending arm 163 projects from a rock shaft 164. The upper end of this arm 163 carries a laterally projecting pin or headed screw 165 that extends through a slot 166 in the link section 135, as best 110 shown in Fig. 10. The rock shaft 164 also carries a depending arm 167 which is controlled from the tabulator mechanism (not shown) in order to effect a forward movement of the two-part link 134, 135 to actuate the ball lock and thereby 115 prevent a depression of any of the numeral keys at the time that tabulator mechanism is operated, as disclosed in my co-pending application Ser. No. 549,852 hereinbefore referred to.

Referring more particularly to Fig. 12 it will be 120 observed that when the platen is in the lower case position, so that the types next to the pivots of the type bars are brought to the printing line, the line indicator 84 will be received in a recess between the types on each type bar in order to 125 register substantially with the upper ends of the printed lower case characters. When the line indicator moves to ineffective position, it moves forward and downward to the dotted line position shown in Fig. 12. When, however, the platen is 130 shifted to upper case position, the line indicator will shift upward with it, and in indicating position will be disposed as shown at 84a in Fig. 12 where it will register substantially with the upper 135 ends of upper case characters printed from the 140 145 150

outermost types on the type bars. At this time the outermost types will pass just beneath the line indicating wire. Therefore, in either case position of the platen the line indicator 84 will substantially indicate where the upper ends of the written characters are to appear, whether such characters be upper or lower case characters.

From the foregoing description it will be understood that I have provided comparatively simple, yet highly effective means for attaining the purposes of the present invention.

Various changes may be made in the construction, and certain features thereof may be employed without others, without departing from my invention as it is defined in the accompanying claims.

What I claim is new and desire to secure by Letters Patent, is:

1. In a front strike typewriting or like machine, the combination of a cylindrical platen, paper feed rollers coacting with the platen above the printing line, deflecting means beneath the platen for receiving a work sheet introduced into the machine from in front of the platen and guiding it beneath the platen, and controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means.

2. In a front strike typewriting or like machine, the combination of a cylindrical platen, paper feed rollers coacting with the platen above the printing line, deflecting means beneath the platen for receiving a work sheet introduced into the machine from in front of the platen and guiding it beneath the platen, and controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means, said controlling means comprising a toggle which when broken withdraws the feed rollers from the platen and when straightened applies the feed rollers to the platen or to a work sheet thereon.

3. In a front strike typewriting or like machine, the combination of a cylindrical platen, paper feed rollers coacting with the platen above the printing line, deflecting means beneath the platen for receiving a work sheet introduced into the machine from in front of the platen and guiding it beneath the platen, controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means, a line indicator, and means controlled by said controlling means for automatically shifting said indicator to indicating position when said feed rollers are shifted towards the platen and for shifting said indicator from indicating position when the feed rollers are withdrawn.

4. In a front strike typewriting or like machine, the combination of a cylindrical platen, paper feed rollers coacting with the platen above the printing line, deflecting means beneath the platen for receiving a work sheet introduced

into the machine from in front of the platen and guiding it beneath the platen, controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means, key locking means, and means controlled by said controlling means for shifting said locking means to locking position when said feed rollers are withdrawn and for shifting the locking means to releasing position when said feed rollers are applied.

5. In a front strike typewriting or like machine, the combination of a cylindrical platen mounted for case shifting movement, paper feed rollers coacting with the platen above the printing line, deflecting means beneath the platen for receiving a work sheet introduced into the machine from in front of the platen and guiding it beneath the platen, and controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means, said feed rollers, deflecting means and controlling means partaking in the case shifting movement of the platen and effective in either case position thereof.

6. In a front strike typewriting or like machine, the combination of a cylindrical platen mounted for case shifting movement, paper feed rollers coacting with the platen above the printing line, deflecting means beneath the platen for receiving a work sheet introduced into the machine from in front of the platen and guiding it beneath the platen, controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means, a line indicator, and means controlled by said controlling means for automatically shifting said indicator to indicating position when said feed rollers are moved towards the platen and for shifting said indicator from indicating position when the feed rollers are withdrawn, said feed rollers, deflecting means, controlling means, line indicating means and shifting means therefor partaking in the case shifting movement of the platen and effective in either case position thereof.

7. In a front strike typewriting or like machine, the combination of a cylindrical platen, paper feed rollers coacting with the platen above the printing line, deflecting means beneath the platen for receiving a work sheet introduced into the machine from in front of the platen and guiding it beneath the platen, controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means, a line indicator, means controlled by said controlling means for automatically shifting said indicator to indicating position when said feed rollers are moved towards

- the platen and for shifting said indicator from indicating position when the feed rollers are withdrawn, key locking means, and means controlled by said controlling means for shifting said locking means to locking position when said feed rollers are withdrawn and for shifting the locking means to releasing position when said feed rollers are applied.
8. In a front strike typewriting or like machine, the combination of a cylindrical platen mounted for case shifting movement, paper feed rollers coacting with the platen above the printing line, deflecting means beneath the platen for receiving a work sheet introduced into the machine from in front of the platen and guiding it beneath the platen, and controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means, said controlling means comprising a toggle which when broken withdraws the feed rollers from the platen and when straightened applies the feed rollers to the platen or to a work sheet thereon, said feed rollers, deflecting means and controlling means partaking in the case shifting movement of the platen.
9. In a front strike typewriting or like machine, the combination of a cylindrical platen, paper feed rollers coacting with the platen above the printing line, deflecting means beneath the platen for receiving a work sheet introduced into the machine from in front of the platen and guiding it beneath the platen, and controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means, said controlling means including a movably mounted support on which the feed rollers are supported and by which they are guided in their movements to and from the platen, and spring means for holding said support against movement until after the feed rollers are brought into contact with the platen.
10. In a front strike typewriting or like machine, the combination of a cylindrical platen; paper feed rollers coacting with the platen above the printing line; deflecting means beneath the platen for receiving a work sheet introduced into the machine from in front of the platen and guiding it beneath the platen; controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means, said controlling means including a movably mounted support on which the feed rollers are supported and by which they are guided in their movements to and from the platen, spring means for holding said support against movement until after the feed rollers are brought into contact with the platen and a toggle which when broken withdraws the feed rollers from the platen and when straightened applies the feed rollers to the platen or to the work sheet thereon and stresses said spring means to apply a spring pressure on the feed rollers, said paper feed rollers, deflecting means and controlling means, partaking of the case shifting movement of the platen and effective in either case position thereof.
11. In a front strike typewriting or like machine, the combination of a cylindrical platen mounted for case shifting movement; paper feed rollers coacting with the platen above the printing line; deflecting means beneath the platen for receiving a work sheet introduced into the machine from in front of the platen and guiding it beneath the platen; and controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means, said controlling means including a movably mounted support on which the feed rollers are supported and by which they are guided in their movements to and from the platen, and spring means for holding said support against movement until after the feed rollers are brought into contact with the platen, said paper feed rollers, deflecting means and controlling means, partaking of the case shifting movement of the platen and effective in either case position thereof.
12. In a front strike typewriting or like machine, the combination of a cylindrical platen mounted for case shifting movement; paper feed rollers coacting with the platen above the printing line; deflecting means beneath the platen for receiving a work sheet introduced into the machine from in front of the platen and guiding it beneath the platen; and controlling means for applying said feed rollers and for effecting a forward and downward withdrawal of the feed rollers from the platen to a position where they not only offer no obstruction to the introduction of a work sheet but will be positioned beneath the same in a position to assist in guiding it to said deflecting means, said controlling means including a movably mounted support on which the feed rollers are supported and by which they are guided in their movements to and from the platen, spring means for holding said support against movement until after the feed rollers are brought into contact with the platen, and a toggle which when broken withdraws the feed rollers from the platen and when straightened applies the feed rollers to the platen or to the work sheet thereon and stresses said spring means to apply a spring pressure on the feed rollers, said paper feed rollers, deflecting means and controlling means, partaking of the case shifting movement of the platen and effective in either case position thereof.
13. The combination of a cylindrical platen, a paper feed roller that coacts with the front of the platen above the printing line and is mounted for movement fore and aft of the machine out of and into contact with the platen and also receives a downward movement relatively to the printing line when withdrawn from the platen and thus provides support on which a work sheet introduced into the machine from in front of the platen may rest and by which it may be guided to and beneath the platen, and means for thus moving said feed roller.
14. The combination of a cylindrical platen, a paper feed roller that coacts with the front of the platen above the printing line and is mounted for movement fore and aft of the machine out of and into contact with the platen and also receives a downward movement relatively to the printing line when withdrawn from the platen and thus provide a support on which a work

- sheet introduced into the machine from in front of the platen may rest and by which it may be guided to and beneath the platen, and means for thus moving said feed roller comprising a 5 toggle which when straightened applies the feed roller to the platen and which when broken withdraws the feed roller from the platen and lowers it to the work sheet guiding position.
15. The combination of a cylindrical platen, 10 a paper feed roller that coacts with the front of the platen above the printing line and is mounted for movement fore and aft of the machine out of and into contact with the platen and also receives a downward movement relatively to the 15 printing line when withdrawn from the platen and thus provides a support on which a work sheet introduced into the machine from in front of the platen may rest and by which it may be guided to and beneath the platen, and means 20 for thus moving said feed roller comprising a slide on which said feed roller is mounted, a support for said slide, and an intermediate pin and cam slot connection between said slide and support for guiding the slide.
25. 16. The combination of a cylindrical platen, a paper feed roller that coacts with the front of the platen above the printing line and is mounted for movement fore and aft of the machine out of and into contact with the platen 30 and also receives a downward movement relatively to the printing line when withdrawn from the platen and thus provides a support on which a work sheet introduced into the machine from in front of the platen may rest and by which it may be 35 guided to and beneath the platen, and means for thus moving said feed roller comprising a slide on which said feed roller is mounted, a pivoted support for said slide, an intermediate pin and cam slot connection be- 40 tween said slide and support for guiding the slide, and a spring which normally holds said support against pivotal movement and which is stressed to apply its force against the feed roller when the latter is forced up on the curved surface of the platen.
45. 17. The combination of a cylindrical platen, a paper feed roller that coacts with the front of the platen above the printing line and is mounted for movement fore and aft of the machine 50 out of and into contact with the platen and also receives a downward movement relatively to the printing line when withdrawn from the platen and thus provides a support on which a work sheet introduced into the machine from in front of the platen may rest and by which it may be 55 guided to and beneath the platen, and means for thus moving said feed roller comprising a slide on which said feed roller is mounted, a pivoted support for said slide, an intermediate 60 pin and cam slot connection between said slide and support for guiding the slide, a spring which normally holds said support against pivotal movement and which is stressed to apply its force against the feed roller when the latter is forced up on the curved surface of the platen, and a 65 toggle connected to said slide and which applies the feed roller to the platen when the toggle is straightened and withdraws the roller from the platen when the toggle is broken.
70. 18. The combination of a platen, paper feed rollers movable to and from the platen, a line indicator movable to and from indicating position, a handle, and means controlled thereby for moving said line indicator towards indicating position at the first part of the movement of 75 the feed rollers towards the platen and for moving the line indicator from indicating position at the first part of the movement of the feed rollers from the platen.
19. The combination of a platen, paper feed rollers, an actuating member movable back and forth, means controlled thereby for moving said feed rollers into and out of contact with the platen, a line indicator movable to and from indicating position, a second actuating member movable back and forth for thus moving said indicator, and means for operating the second actuating member at the first part of each of the forward and back movements of the first 80 mentioned actuating member.
20. The combination of a platen, paper feed rollers, an actuating member movable back and forth, means controlled thereby for moving said feed rollers into and out of contact with the platen, a line indicator movable to and from indicating position, a second actuating member movable back and forth for thus moving said indicator, and means for operating the second actuating member at the first part of each of the forward and back movements of the first 85 mentioned actuating member, said means comprising a link connected to the first mentioned actuating member and having an abutment that engages the second actuating member on one side and moves it during the movement of the link in one 90 direction and engages on the other side of the second actuating member during the movement of the link in the opposite direction, and means for thus effecting an engagement between said link and second actuating member.
21. The combination of a platen, paper feed rollers, an actuating member movable back and forth, means controlled thereby for moving said feed rollers into and out of contact with the platen, a line indicator movable to and from indicating position, a second actuating member movable back and forth for thus moving said indicator, and means for operating the second actuating member at the first part of each of the forward and back movements of the first 100 mentioned actuating member, said means comprising a link connected to the first mentioned actuating member and having an abutment that engages the second actuating member on one side and moves it during the movement of the link in one 105 direction and engages on the other side of the second actuating member during the movement of the link in the opposite direction, and means for thus effecting an engagement between said link and second actuating member.
- 110
22. The combination of a platen mounted for case shifting movement, a work sheet deflector arranged beneath the platen and shifting therewith in its case shifting movements and mounted for independent movement to and from the platen, and manually controlled means for effecting such independent movement of the deflector in either case position of the platen, key locking means, 115 and means controlled by said manually controlled means for shifting said key locking means to and from locking position.
23. The combination of a platen mounted for case shifting movement, a work sheet deflector 120
- 125
- 130
- 135
- 140
- 145
- 150

- arranged beneath the platen and shifting therewith in its case shifting movements and mounted for independent movement to and from the platen, a ribbon vibrator support shiftable with the platen in its case shifting movements and also independently shiftable from normal position in either case position of the platen, and manually controlled means operable at will for effecting such independent movements of the deflector and ribbon vibrator support in either case position of the platen. 80
24. The combination of a platen mounted for case shifting movement, a work sheet deflector arranged beneath the platen and shifting therewith in its case shifting movements and mounted for independent movement to and from the platen, a ribbon vibrator support shiftable with the platen in its case shifting movements and also independently shiftable from normal position in either case position of the platen, manually controlled means operable at will for effecting such independent movements of the deflector and ribbon vibrator support in either case position of the platen, key locking means, and means controlled by the said independent movement of the ribbon vibrator support from and to normal position for controlling said key locking means. 85
25. The combination of a cylindrical platen mounted for case shifting movement, two paper deflectors that shift with the platen and are arranged one above the other beneath the platen and provide a work sheet receiving channel between the platen and the upper deflector and a second work sheet receiving channel between the two deflectors, the lower deflector having a pivoted front section movable to and from a fully opened position, feed rollers movable to and from the platen and shiftable therewith in its case shifting movements, and automatically operating means for lowering said pivoted deflector section when the feed rollers are moved from the platen so as to open the channel between the two deflectors for the ready insertion of a work sheet. 90
26. The combination of a platen, a paper feed roller, a carrier movable towards and from the platen and on which said feed roller is mounted, supporting means for said carrier, means for moving said carrier, and guiding means intermediate said supporting means and carrier for causing the carrier when moved towards the platen to first receive a pivotal movement and then to receive a rectilinear sliding movement to move the feed roller against the platen. 95
27. The combination of a platen, a paper feed roller, a carrier movable towards and from the platen and on which said feed roller is mounted, supporting means for said carrier, means for moving said carrier, and guiding means intermediate said supporting means and carrier for causing the carrier when moved away from the platen to first receive a rectilinear sliding movement and then to receive a downward pivotal movement to lower the feed roller after it has been withdrawn from the platen. 100
28. The combination of a platen, a paper feed roller, a carrier movable towards and from the platen and on which said feed roller is mounted, supporting means for said carrier, a manually controlled toggle for moving said carrier, and guiding means intermediate said supporting means and carrier for causing the carrier when moved away from the platen to first receive a rectilinear sliding movement and then to receive a downward pivotal movement to lower the feed roller after it has been withdrawn from the platen. 105
29. In a front strike typewriting machine, the combination of a cylindrical platen, a paper feed roller that coacts with the platen above the printing line, a sliding and swinging carrier on which said feed roller is mounted and which controls the movement of the feed roller to and from the platen, supporting means for said carrier, means for moving said carrier, and guiding means on said supporting means and carrier for causing the carrier to receive first a rectilinear sliding movement away from the platen and then to receive a downward swinging movement so as to first effect a straight line movement of the feed roller from the platen and then effect a lowering of the feed roller to a position where it offers no obstruction to the ready insertion of a work sheet into the machine from in front of and beneath the platen. 110
30. The combination of a platen, a feed roller cooperative therewith above the printing line, a carrier for said feed roller having two aligned slots therein that extend longitudinally of the carrier, the slot nearest the platen having an upward extension at substantially right angles to the aligned portion of the slot, supporting pins or members in said slots, and means for moving said carrier, whereby the feed roller when withdrawn from the platen will first be withdrawn with a rectilinear forward motion and then will be lowered relatively to the printing line. 115
31. The combination of a platen, a paper feed roller, a carrier movable towards and from the platen and on which said feed roller is mounted, supporting means for said carrier, means for moving said carrier, guiding means intermediate said supporting means and carrier for causing the carrier when moved towards the platen to first receive a pivotal movement and then to receive a rectilinear sliding movement to move the feed roller against the platen, key locking means and means for shifting said locking means to locking position when the feed roller is moved away from the platen and for shifting the locking means to releasing position when the feed roller is moved towards the platen. 120
32. The combination of a platen mounted for case shifting movement, means for conditioning the machine to receive a work sheet, key locking means, and automatically operating means for shifting said key locking means to locking position when the machine is being conditioned to receive a work sheet and irrespective of the case position of the platen, said last mentioned means including two cams, and means for bringing one or the other of said cams into use depending on the case position of the platen. 125
33. The combination of a cylindrical platen, a work sheet receiving chute arranged beneath the platen and comprising a section thereof that has an independent movement towards and away from the platen, feed rollers movable into and out of contact with the platen, automatically operating means for moving said chute section towards the platen when the feed rollers are moved towards the platen and for moving said chute section away from the platen when the feed rollers are moved away from the platen, key locking means, and automatically operating means for shifting said locking means to locking position when said chute section is moved away from the platen. 130
34. The combination of a cylindrical platen, means for mounting said platen for case shift- 135
- 75

ing movement, paper feed rollers movable towards and from the platen, key locking means, and automatically operating means for shifting said key locking means to locking position when 5 the feed rollers are moved away from the platen whether the platen be in the lower case or in the upper case position.

35. The combination of a platen, paper feed rollers, a line indicator movable to and from indicating position, and automatically operating means for moving said indicator from indicating position at the initial part of the movement of said feed rollers away from the platen, the construction and arrangement of the parts being such that said automatically operating means start to function as soon as said feed rollers start to move away from the platen.

36. The combination of a platen, paper feed rollers, a line indicator movable to and from indicating position, and automatically operating means for moving said indicator from indicating position at the first part of the movement of said feed rollers from the platen and for moving said indicator to indicating position at the first part of the movement of the said feed rollers towards the platen and for maintaining the indicator in such indicating position through-

out the completion of the movement of the feed rollers to the platen.

37. The combination of a platen, paper feed rollers, a line indicator movable to and from indicating position, automatically operating means for moving said indicator from indicating position at the first part of the movement of said feed rollers from the platen and for moving said indicator to indicating position at the first part of the movement of the said feed rollers towards the platen and for maintaining the indicator in such indicating position throughout the completion of the movement of the feed rollers to the platen, and manually controlled means for moving said line indicator to and from indicating position independently of the said movements of the feed rollers.

38. The combination of a platen, paper feed rollers, a line indicator movable to and from indicating position, and automatically operating means for moving said indicator immediately to indicating position at the initial part of the movement of said feed rollers towards the platen and for moving the indicator immediately from indicating position at the initial part of the movement of said feed rollers away from the platen.
